UNITED STATES PATENT OFFICE

147,713

DESIGN FOR A GAME BOARD

Robert E. Zimmerman, Greensboro, N. C.

Application June 1, 1946, Serial No. 130,330

Term of patent 14 years

(Cl. D34—5)

To all whom it may concern:

Be it known that I, Robert E. Zimmerman, a citizen of the United States, residing at Greensboro, in the county of Guilford and State of North Carolina, have invented a new, original, and ornamental Design for a Game Board, of which the following is a specification, reference being had to the accompanying drawing, forming part thereof.

The figure is a top plan view of a game board, showing my new design.

The thickness of the board is conventional.

I claim:

The ornamental design for a game board, as shown and described.

ROBERT E. ZIMMERMAN.
